(57) **CLAIM**

The ornamental design for a propane tank asymmetric backless bench, as shown and described.

DESCRIPTION

FIG. 1 is a top side perspective view of the propane tank asymmetric backless bench showing my new design;
FIG. 2 is bottom side perspective view of the propane tank asymmetric backless bench showing my new design;
FIG. 3 is a front elevational view of the propane tank asymmetric backless bench showing my new design;
FIG. 4 is a side elevational view of the propane tank asymmetric backless bench showing my new design;
FIG. 5 is a back elevational view of the propane tank asymmetric backless bench showing my new design;
FIG. 6 is top plan view of the propane tank asymmetric backless bench showing my new design; and,
FIG. 7 is side elevational view of the propane tank asymmetric backless bench showing my new design.
